Filed June 13, 1961, Ser. No. 65,578

Term of patent 14 years

(Cl. D15—3)

FIGURE 1 is a front perspective view of a dental chair seat showing our new design for the seat member thereof; FIGURE 2 is a top plan view of the seat member; and FIGURE 3 is a side elevational view thereof. The side and rear edge portions of the seat not shown in FIGURE 1 are plain and unornamented. The dotted lines employed in FIGURE 1 are for illustrative purposes only.

We claim:
The ornamental design for a dental chair seat or similar article, substantially as shown and described.
